UNITED STATES PATENT OFFICE.

WILLIS F. SPROUT, OF LEBANON, KANSAS.

PROPORTIONAL DIVIDERS.

Application filed December 30, 1924. Serial No. 758,816.

The primary object of the invention is to provide a tool for readily and quickly locating uniformly spaced points in a given length, so that the mental calculation of 5 such division may be done away with and so that the points may be located with a nicety not possible with a rule or dividers; to provide a tool particularly adapted for laying off the divisions necessary in the 10 construction of sash and doors, thus materially reducing the time necessary to be employed by the "bar man" in such operation; and to provide a tool which may be easily and cheaply constructed and, therefore, 15 marketable at a low cost.

With this object in view, the invention consists in a construction and combination of parts of which a preferred embodiment is illustrated in the accompanying drawings, 20 wherein:

Figure 1 is a plan view of the invention shown in extended position.

Figure 2 is a similar view showing the tool closed.

Figure 3 is a detail sectional view on the line 3—3 of Figure 1.

Figure 4 is a similar view on the line 4—4 of Figure 3.

Figure 5 is a section on the line 5—5 of 30 Figure 1, and

Figure 6 is a sectional view on the plane indicated by the line 6—6 of Figure 1.

Constructed on the plan of lazy tongs, the device consists of a plurality of bars 1 pivotally connected at intermediate points in their length, as at 2, and pivotally connected terminally, as at 3 and 4. The terminal links 5 are half the length of the bars and have their terminals pivotally connected at 40 6. The pivotal connections 2 and 3 consist merely of rivets connecting the crossing and terminally connected bars 1 but the pivotal connections 4 consist of pivot pins 7 protruding beyond the plane of the bars on one 45 side of the device and having conical terminals 8 for penetration into the surface measured to anchor the tool at the extremities of the length to be divided.

In the illustrated embodiment, a pin 7 is 50 provided at each extremity of the tool and additional pins provided at pivotal connections of the next succeeding bars, so that the tool may be readily adapted for determining different divisions within a specified range.

55 For example, if the pivot pins 7 at the op-

posite terminals be placed at the extremities of the length to be measured, every pivot point 4 between them and in line with the same will represent a division point or, if the number of divisions is a factor of the 60 number of pivot points between the two, the marking or spotting may be made opposite the necessary pivot points. By providing the pins 7 at one end and at adjacent pivot points at that end, almost every conceivable 65 number of divisions may be had, it being only necessary to select one of the plurality of pins 7 at one end and the pin 7 at the other end as the working extremities of the tool.

In order to provide the necessary gauges for marking and thus make it unnecessary to spot from the pivot points, there is provided between each of the bars 1 at the ends connected by the pins 4 and the rivets in 75 line therewith, a plate 9 having a marking notch 10 and in order that this marking notch may be always above the point of pivotal connection of the bars, the plate is provided with a longitudinal slot 11 traversed by the rivet 4 or the pin 7, depending on the point at which the plate is positioned. Further, there is provided in each plate the transverse slots 12 and 14, one of which is 80 engaged by a pin 15 on one of the bars 1 and the other by a pin 16 on the bar pivotally connected with the first bar. Thus, as the tool is spread or opened, the pins 15 and 16 tend to maintain the plate with that edge having the notch 10 therein in a position 85 parallel with the longitudinal axis of the tool. Thus, the notches 10 define the division point in the laying off of a piece of work.

To retain the tool in closed position, a 90 latch plate 17 is provided, having a pivotal connection with the pin 7 at one end of the tool. When the tool is in use and it is necessary that it be extended and contracted, the latch plate is terminally engaged at the opposite ends with a knob 18 carried by the pivotal connection between the links 5, the latch plate having a notch 19 in one end for engagement with said knob. When the tool is not in use and in closed or contracted position, the notch 19 of the latch plate is engaged with the head of the pin 7 at the other end of the tool, as shown, and thus the tool is retained in closed position. The latch plate is dimensioned according to the links 100 110

5 and the tool when in closed position has a corresponding length on a line between the terminal pins 7.

The invention having been described, what 5 is claimed as new and useful is:

A tool for the purpose indicated comprising a plurality of pivotally connected bars arranged in the form of lazy tongs and provided with means on one line of pivotal connections for locating division points between 10 the terminals of the connected series, and a

latch plate dimensioned according to one of the terminal links and having a pivotal connection therewith coincident with that link's connection with the next link, said latch plate having a notch adapted to selectively engage a knob at the adjacent end of the series of links or one at the remote end of the series when the series is folded.

In testimony whereof he affixes his signature. 20

WILLIS F. SPROUT.
